Attorney:

UNITED STATES PATENT OFFICE.

LAMAR H. SHOVER, OF MILWAUKEE, WISCONSIN.

CANDY JAR.

Application filed July 3, 1922. Serial No. 572,687.

To all whom it may concern:

Be it known that I, LAMAR H. SHOVER, a citizen of the United States, and resident of Milwaukee, in the county of Milwaukee and State of Wisconsin, have invented certain new and useful Improvements in Candy Jars; and I do hereby declare that the following is a full, clear, and exact description thereof.

10 This invention pertains to a device for regulating the humidity within a closed jar or container.

15 The primary object of the invention resides in the provision of a simple and economical device of the above character, which does not require a specially constructed jar, but is applicable to any standard or conventional type, such as glass candy or cigar jars provided with the usual hollow cap.

20 A more specific object is to provide a humidity regulator with resilient means for engaging the interior of a hollow cap, whereby the device is detachably retained within the cap.

25 With the above and other objects in view, which will appear as the description proceeds, my invention resides in the novel construction, combination and arrangement of parts, substantially as hereinafter described and more particularly defined by the appended claims, it being understood that such changes in the precise embodiment of the herein disclosed invention may be made as come within the scope of the claims.

30 In the accompanying drawing, I have illustrated one complete example of the physical embodiment of the present invention constructed according to the best mode 40 I have so far devised for the practical application of the principles thereof, and in which:—

35 Figure 1 is a vertical sectional view through a humidity regulator constructed in accordance with the present invention and showing the same applied to a conventional type of glass candy jar.

45 Figure 2 is a plan view of the invention, with parts broken away to more clearly illustrate the structural features.

50 Referring now more particularly to the accompanying drawings, the present invention, which is designed to reduce or increase the humidity within a container, comprises

a housing consisting of a cylindrical cup 35 3 having perforations in its bottom and side wall and provided with a cover or closure 4 projecting slightly beyond the outer periphery of the cup. Positioned within the housing is a porous pad 5, of any suitable 40 material, adapted to be saturated with a moistening material, where it is desired to increase the humidity within the jar, or with a moisture absorbing material where it is desired to reduce the humidity.

In the present instance, the housing is shown positioned within the mouth of a hollow cap 6, which cap is provided with an annular contracted portion 7 engaged by a plurality of resilient radial arms 8 secured to the housing by means of a bolt 9 passing through the cover 4 and the cup 3, which bolt, in addition to securing the resilient arms to the cover, also serves to lock the entire assembled device together, the bolt being provided with a knurled thumb nut 10.

From the foregoing it is obvious that the device can be readily disassembled when it is desired to change the pad contained in the housing to either decrease or increase the humidity, and it will also be seen that the resilient means provided enables the device to be quickly inserted or removed from a conventional hollow cap, the resilient arms compensating for slight variation in size and shape of the cap.

Attention is also directed to the fact that the projecting cover 4, which abuts the annular contracted portion 7 of the cap, serves to space the cup from the sides of the cap, thereby enabling the air to entirely surround the perforated sides of the cap, insuring the efficient action of the device in either decreasing or increasing the humidity within the container.

I claim:—

1. A device of the character described, comprising a perforated housing adapted to receive a pad, and resilient members carried by the housing adapted to engage the 100 interior of a hollow cap to detachably retain the housing within the cap.

2. A device of the character described, comprising a housing consisting of a circular perforated cup adapted to receive 105 a porous pad, a cover for the cup, resilient radial arms adapted to engage the interior of a hollow cap to retain the housing with-

in the cap, and a bolt passing through said resilient arms, cover, and cup, to lock said parts together.

3. A device of the character described, comprising a perforated circular housing adapted to encase a porous pad, and resilient radial arms secured to the housing and adapted to engage the contracted interior portion of a hollow cap to detachably retain the housing within the cap.

4. In combination with a hollow cap having a restricted annular portion, a housing adapted to be inserted in the mouth of said cap and abut the restricted portion, a porous pad positioned within the housing, and a plurality of resilient radial arms carried by the housing and adapted to engage the re-

stricted portion of the cap to retain the housing within the same.

5. In combination with a hollow cap having a restricted annular portion, a housing comprising a circular perforated cup adapted to receive a porous pad, a cover for said cup, said cover projecting past the periphery of the cup and abutting the annular portion of the cap whereby the cup is spaced from the side wall of the cap, and resilient means carried by the housing for retaining the same within the cap.

In testimony that I claim the foregoing 30 I have hereunto set my hand at Milwaukee, in the county of Milwaukee and State of Wisconsin.

LAMAR H. SHOVER.
